UNITED STATES PATENT OFFICE.

ARTHUR F. KLAUSCHIE, OF OMAHA, NEBRASKA.

TELEPHONE ATTACHMENT.

1,316,366.

Specification of Letters Patent. Patented Sept. 16, 1919.

Application filed February 24, 1919. Serial No. 278,697.

To all whom it may concern:

Be it known that I, ARTHUR F. KLAUSCHIE, a citizen of the United States, residing in the city of Omaha, county of Douglas, 5 and State of Nebraska, have invented a certain new and Improved Telephone Attachment, and have described the same in the following specification, illustrated by the accompanying drawings.

10 My invention relates to that class of adjustable and removable attachments which are commonly applied to telephones and are individually adapted to secure thereto a scratch-pad and other appliances repeti-
15 tiously as occasion or convenience may re-
quire. It is the main object of the invention to render an attachment of this kind ap-
plicable to the stem and base of the ordi-
nary transmitter stand in an easy and ad-
20 justable manner; to fix the scratch-pad in an inclined position convenient to be writ-
ten on; to render an operative portion, or tablet, of the attachment available for the
advantageous display of advertising matter,
25 telephone addresses, or other characters or
information impressed, printed, affixed or
marked thereon; to facilitate the manufac-
ture of the attachment and reduce the cost
thereof, by stamping its body integrally
30 from a single piece of sheet metal; and in
general to produce a simple and superior
article of the specified class. To accom-
plish these objects I incorporate in my im-
proved telephone attachment, as parts there-
35 of, a pair of spring arms adapted to hug
the stem of the transmitter stand, a clasp
extending from one of the arms to hold a
pencil, a tablet extending vertically along
the stem, and a pad-plate sloping from the
40 tablet, all formed from a single sheet of
metal, and provided with a spring-actuated
presser-foot pivotally mounted on the tablet.

In said drawings, illustrating the best
manner in which I have contemplated ap-
45 plying the principles of my invention, Fig-
ure 1 is a perspective view of a telephone
attachment which is constructed in accord-
ance with these principles and is exhibited
as operatively applied to a telephone, and
50 as holding a scratch-pad and pencil. Fig. 2
is a side elevation of the same attachment
and the pad held thereby. Fig. 3 is an in-
complete horizontal section of the same on
the section line 3-3 in Fig. 2. Fig. 4 is a
55 plan of the flat body of the attachment as
stamped from a piece of sheet metal and

ready to be bended on the several broken
lines in the process of manufacture. In this
plan the several parts of the blank are de-
noted respectively by the same numerals 60
which denote the corresponding parts of
the completed structure in the other figures.

In this illustrative specimen of my in-
vention, the pad-plate is denoted by the nu-
meral 1. It bears contactually upon the 65
convex or conical top surface of the base 2
of the telephone stand in a correspondingly
inclined or sloping position, and is slightly
longer and wider than the scratch-pad 3
which lies flat thereon. The vertically dis-
70 posed tablet 4, being an arm of the plate 1,
contacts from end to end with a portion of
the stem 5 of the transmitter stand, and is
fitted thereto. It is operatively secured to
the stem by its opposing snap arms 6 and 6' 75
of unequal length, which hug the stem and
are circumferentially adjustable thereon. It
extends along the side of the stem above the
level of these arms, and thus not only sup-
plies on its exposed front side a display 80
space for advertisements and the like which
may be exhibited thereon, but also serves as
a lever to resist all tendency of the pad-
plate to be tilted upward or away from the
base 2 when the attachment is in use in con-
85 nection with a scratch-pad. Similarly the
arm 6' has a pair of co-acting spring fingers
8, which form a clasp adapted to hold in an
out-of-the-way and oblique position, and as
often as may be desired, a lead pencil or 90
the like, convenient for use upon the scratch-
pad 3. This pad, which is severable leaf by
leaf along the broken line 9, is held in its
normal and delineated position by the
presser-foot 10, which may be manually 95
lifted by the toe 11 to permit the normal
placing of the pad; and this foot, actuated
by the spring 12, is pivoted on the pin 13
connecting the ears 14 of the tablet 4.

Such being the construction and operation 100
of my improved telephone attachment, the
same possesses the several operative and man-
ufacturing advantages which were above
stated as constituting the main object of the
invention. The entire attachment is adjust-
105 able rotarily on the stand, and about the
axis of the stand, to any angular position
which the convenience of the operator may
dictate; the superposition of the pad-plate
immediately upon the base 2, prevents the 110
latter from being tilted by any downward
pressure which the writer may exert upon

the pad, and also counteracts all tendency of the tablet 4 to be tilted from the stem 5 by the same pressure; the location of the spring fingers 8 of the arm 6' at a distance 5 from the junction of this arm with the tablet 4, is facilitated by the superior length of this arm as compared with the arm 6, and permits the pencil 8 to be inserted in the clasp in the oblique position shown, where 10 it will not hide from view anything written on the pages of the scratch-pad; and the arrangement of parts which permits the pad-plate, the tablet 4, the ears 14, the snap-arms 6 and 6', and the spring fingers 8, to be 15 stamped integrally from a metallic sheet by a single operation, simplifies the construction of the device and lessens its cost of manufacture.

I claim as my invention:

20 1. A telephone attachment comprising a pad-plate fitted to rest upon the base of the

telephone stand, a tablet contacting continuously with the stem of the stand, a pair of spring arms adapted to hug the stem, a pencil clasp extending from one of the arms, 25 all stamped from a single piece of sheet metal, and provided with a spring-actuated presser-foot for engaging a scratch-pad.

2. A telephone attachment comprising a plate for the support of a scratch-pad, a 30 tablet having a pair of ears and forming a vertical arm of the plate, a pair of snap arms of unequal length extending from the tablet to clasp the stem of the telephone stand, and a pencil clasp carried by the 35 longer of said snap arms, all stamped from a single sheet of metal, in combination with a spring-actuated presser-foot pivoted to said ears.

Witness my signature at Omaha, Ne- 40
braska, February 21, 1919.

ARTHUR F. KLAUSCHIE.
